Application May 15, 1945, Serial No. 593,814

27 Claims. (Cl. 51—267)

1

This invention relates to grinding, and more particularly to a method and apparatus for making it possible for a given grinding wheel to perform materially heavier grinding duty with materially increased length of life of the wheel.

As conducive to a clearer understanding of certain objects and features of this invention, it might at this point be noted that the rate, cost and efficiency of grinding of work pieces, such as parts made of steel, alloys, and various other metals, both hard and soft, are limited and held down, in heretofore known methods and apparatus, by a number of factors, such as depth of cut which the grinding wheel can take, rate of relative feed or traverse between the work and the grinding wheel, wheel wear, character of finish produced, frequency of wheel truing (which also greatly affects the life of the wheel), temperatures produced at the grinding line and also in the work, and the like; this is true even if the best heretofore known coolants or cutting fluids are employed according to the best heretofore known standards. If, for example, the attempt is made to increase production as by taking heavier cuts or increasing rate of feed beyond the optimum, loading and breakdown of the wheel face and shortened life thereof and increased power consumption together with poor finish of the work and need of more grinding passes and other detrimental factors result, and hence it has been heretofore impossible to increase grinding production or efficiency and to lower cost of grinding beyond the limitations inherent in the optimum conditions for the different types or kinds of work pieces to be operated upon. This is true for various types of grinding, such as surface grinding, internal and external grinding of round or cylindrical surfaces, etc., etc., and these limitations become still more restrictive where the grinding wheel is called upon to function by way of both surfaces of its corner or corners, as, for example, when the wheel, as in crankshaft grinding, has to function by way of its outer cylindrical surface and its two side faces as well; in such cases, the burden at the corner or corners of the wheel is multiplied, the corner or corners break down or wear too rapidly if the grinding burden is too heavy, and the shortening of wheel life by too frequent truing of the cylindrical face to restore the corners becomes prohibitive. We have discovered a method and apparatus, applicable to such types of grinding operations or their corresponding grinding machines as above mentioned, whereby such limitations as those above mentioned are substantially lifted and whereby such grinding

2

machines may be operated and their grinding operations performed at a level of rate and efficiency of grinding heretofore unachieved and heretofore impossible of achievement by known grinding methods or apparatus.

Other objects of this invention are to provide a grinding method and apparatus of the just-mentioned nature that can be efficiently and economically put into practice and that will be readily and inexpensively adaptable to known types of grinding machines and applicable in general to grinding machines, particularly to those types where relative traverse movement between the work and grinding wheel to effect progression of the grinding cut takes place, or relative traverse in successive strokes accompanied by successive wheel feed take place, or the like. Another object is to provide a method and apparatus for increasing the capacity of a given grinding wheel. Another object is to provide a method and apparatus for increasing the life of a grinding wheel. Another object is to provide a method and apparatus for grinding in which the grinding wheel may be made to perform at greater than heretofore-considered normal capacity, at better wheel life, and at the same or materially lessened power input. Another object is to provide a method and apparatus for protecting the grinding wheel and the workpiece, under conditions of increased duty of the grinding wheel, against loading of the wheel and detrimental breakdown of the wheel and against temperature conditions in both the wheel and the work as are detrimental to either or both. Another object is to provide a practical and efficient method and apparatus for controlling the application to the grinding wheel and workpiece of a plurality of coolant and grinding liquids in a manner to effect increased grinding performance and efficiency of wheel while achieving the desired standard of finish on the workpiece and maintaining economical wheel life. Another object is to provide a method and apparatus for carrying out the last-mentioned object in a manner to permit wide range of change of control or action to meet widely varying practical requirements and kinds or types of grinding operations. Another object is to provide an easily-controlled flexibility or variability of action and application of a plurality of liquid coolants or grinding liquids to the grinding wheel and workpiece to meet different conditions met with in the grinding of certain kinds or shapes of workpieces and also to meet varying conditions imposed by different kinds or shapes of workpieces or different grinding operations. Another object is in general to achieve su-

terior grinding and longer wheel life than has heretofore been possible. Other objects will be in part obvious or in part pointed out hereinafter.

The invention accordingly consists in the features of construction, combinations of elements, arrangements of parts and in the several steps and relation and order of each of the same to one or more of the others thereof, all as will be illustratively described herein, and the scope of the application of which will be indicated in the following claims.

In the accompanying drawings in which are shown several illustrative embodiments and applications of the mechanical features of our invention,

Figure 1 is a schematic or diagrammatic representation of an apparatus for practicing our invention;

Figure 2 is a fragmentary diagrammatic front elevation as it would be seen from the left in Figure 1, illustrating the application of our invention to one known form or type of grinding machine;

Figure 3 is a fragmentary schematic view or representation, as it would be seen from above in Figure 1, illustrating another type or kind of grinding operation to which our invention is applicable;

Figure 4 is a side elevation on an enlarged scale showing a preferred form of apparatus or device employed in carrying out our invention and indicating diagrammatically certain actions that it achieves;

Figure 5 is an elevation as seen from the right in Figure 4, certain parts being omitted;

Figure 6 is a diagrammatic representation to indicate certain actions that take place on the surface of the grinding wheel at and adjacent to the grinding line;

Figure 7 is a fragmentary vertical sectional view on an enlarged scale as seen along the line 7-7 of Figure 5;

Figure 8 is a view like that of Figure 6 representing diagrammatically certain actions resulting from certain adjustments;

Figure 9 is a fragmentary representation in diagrammatic perspective indicating certain actions at the corner of a grinding wheel;

Figure 10 is a fragmentary schematic view or representation, as seen from above, illustrating a corner grinding operation;

Figure 11 is a diagrammatic or schematic representation in front elevation illustrating one form of embodiment of our invention in surface grinding;

Figure 12 is an end elevation as seen from the right in Figure 11, certain parts being omitted;

Figure 13 is a view like that of Figure 11 illustrating a possible modified control; and

Figure 14 is a diagrammatic representation illustrating certain separating and treatment apparatus of our invention.

Similar reference characters refer to similar parts throughout the several views of the drawings.

As above indicated, the method and apparatus of our invention are applicable generally to grinding operations and grinding apparatus; our invention is probably best illustrated with respect to such grinding machines in which a grinding wheel performs a grinding operation upon a round or cylindrical surface of a metal workpiece which is supported and rotated during the grinding operation, suitable means being provided for

effecting relative movement between the workpiece and the grinding wheel for various purposes, such as for example, for axially progressing the workpiece relative to the grinding wheel or vice versa, for effecting "feed," thus to determine the depth of cut of the grinding wheel, for effecting relative movement between the workpiece and the grinding wheel in a direction transverse to the axis of the rotating workpiece as when one or both of the side faces of the grinding wheel are to grind portions of the workpiece, with or without having the peripheral face of the wheel performing a grinding operation, and the like, and to achieve greater simplicity of description and to avoid limitation by implication, any such apparatus, chosen for illustration of the applicability of our invention, is indicated in the drawings by a simple representation of a grinding wheel G and a workpiece W which may be supported and rotated by any suitable means not shown and traverse feed and other movements, relative or otherwise, are simply indicated by appropriate arrows. Any well known form of grinding machine may be employed and for greater facility of description it may be assumed, but not by way of limitation, that the workpiece is mounted on centers and driven at suitable speed and in suitable direction.

Supported in any suitable way, from any suitable part of the apparatus—conveniently from the heavy guard 10 that covers over or encloses most of the grinding wheel G—is a device generally indicated by the reference character 11 constructed and adapted to supply a plurality of liquids for coaction with the grinding wheel G and the workpiece W, and a preferred and illustrative construction of which is shown in larger scale in Figures 4 and 5, to which reference may now be made.

The device 11 comprises a nozzle 12 or other suitable device for discharging and generally directing a liquid preferably in large volume and preferably at low pressure; it is to handle a liquid, the principal or primary characteristic of which is that it have good capacity for abstracting heat and, hence, we refer to it as a coolant liquid. The nozzle 12 we may term a coolant liquid nozzle or a low-pressure nozzle. It is conveniently made of steel piping of suitable diameter and length, being provided at its upper end with suitable means for connecting it into a liquid circulating or liquid pumping system, and conveniently the upper end may be threaded, as at 13, to receive a pipe coupling 14 (Figure 1) by which it may be connected to other conduits or pipes diagrammatically indicated at 15.

Its lower end curves inwardly from the vertical axis of the part 12 and, hence, toward the grinding wheel G, as viewed in Figures 1 and 4, and, where made up of round tubing, its lower end preferably also is shaped—as by flaring it out laterally to both sides of its vertical axis, as viewed in Figure 5, and by progressively narrowing it in internal and external dimensions, as viewed in Figure 4—to provide a discharge mouth M that is of a length commensurate with the width of the peripheral face P of the grinding wheel G and, hence, is of a length commensurate with the length of the grinding line L along which the work is contacted by the wheel face P. The mouth M may thus be of generally rectangular area or shape, and may have uniform transverse dimension or width, and thus it is capable of discharging coolant liquid in large volume, prefer-

ably in the manner hereinafter described, at not only a uniform rate per unit area of the mouth M, but also at substantially uniform volume per unit length of the mouth M.

In so shaping the mouth end of the tube 12, we are enabled also to provide, upon that wall of the mouth nearest the grinding wheel G, a flat or plane portion 17 along or by which is suitably aligned or related to the mouth M of the nozzle 12, suitable discharge means for a liquid, the principal or primary characteristic of which is to promote the action of cutting or grinding at the grinding line and throughout the relatively small area or region where such action takes place; this liquid we sometimes term herein the active liquid or the grinding liquid, and, since, in a preferred embodiment of the invention, we apply it at relatively high pressure and in low volume, the discharge means for it—which, illustratively, comprises one or more nozzles—we sometimes term herein as a high-pressure nozzle or nozzles. If more than one nozzle is employed, they may be aligned along the flat portion 17 of nozzle device 12, and an illustrative number for an illustrative width of grinding wheel face is three—best indicated in Figure 5 by the reference characters 19, 20, and 21. For example, where the mouth M of the coolant liquid nozzle has a length on the order of three inches for a width of grinding wheel face P of about three inches, the high-pressure or active liquid nozzles 19, 20, and 21 have discharge orifices which are preferably and most conveniently circular in shape and of a diameter on the order of one-sixteenth of an inch, and their distribution along the length of the mouth M is preferably substantially uniform and an illustrative distribution may be like that indicated in Figure 5.

The nozzles 19, 20, and 21 are arranged to be connected to a supply system, preferably a pressure circulating or pumping system later described and the piping or conduit of which is indicated at 23 in Figure 1, and preferably the supply of liquid and the action of each nozzle are controllable and regulatable for reasons later described.

A convenient, illustrative, and preferred arrangement for coupling the individual nozzles to the conduit 23 may be like that shown in Figures 4, 5, and 7. Thus, the flat wall 17 (Figure 5) of the low-pressure nozzle 12 may be slotted, as by milling, at its lower end as indicated at 25, 26 and 27 so as to receive therein blocks 28, 29 and 30, respectively, preferably shaped, constructed and mounted in the manner illustrated in enlarged scale in Figure 7 with respect to the block member 28. Thus its front face 28^a is preferably aligned with the front face of the flat wall 17 as it is fitted into its slot 25, and it is preferably welded or brazed or otherwise secured in position to the wall portion 17. It has an upper face 28^b which extends substantially at right angles to the front face 28^a and hence to the plane of the flat front wall 17 and contains an angular channel 31 formed as by drilling from the top face 28^b and also by drilling from the inclined portion 28^c of the front face. The outwardly exposed end of channel 31 is preferably constructed to detachably and adjustably mount therein the high pressure nozzle 19 and preferably the latter is constructed to have a threaded shank 19^a receivable into the downwardly and outwardly exposed end of the channel 31 which is threaded as indicated at 31^a; through the nozzle element 19 is a passage 33 conveniently formed as by drilling and serving

also as an orifice. Preferably, orifice channel 33 extends at an angle to the axis of the threaded shank 19^a, illustratively an angle on the order of 25°, so that, by changing the rotary position of the nozzle element 19 about the just-mentioned axis, the point at which the emerging stream of liquid impinges upon the face P of the grinding wheel may be shifted both horizontally and vertically, that is, to the right or left as viewed in Figure 5 and up or down as viewed in Figure 4.

To simplify the control of the setting of the orifice element 19, the fit of the threaded shank 19^a in the threaded channel part 31^a is preferably made relatively tight and hence self-locking or self-holding against unintentional rotary movement and the shank 19^a is provided with an external larger-diameter portion 19^b which may be given an external hexagonal or other suitable shape to permit application thereto of a wrench or may be slotted as at 19^c to permit engagement of a tool like a screw driver. Thus ease of rotary adjustment and dependable maintenance of the desired setting are achieved.

The other end of channel 31 which, in the illustrated preferred structure is exposed internally of the tube 12, is constructed to have a relatively small tube or pipe 32 connected to it, conveniently as by providing that end of the channel 31 as with a socket 31^b and to receive the tube 32, a sealed connection being effected as by soldering or sweating the two parts together.

Where more than one high pressure nozzle element is employed, and as will now be clear, they are similarly constructed and mounted as just described with respect to the orifice-nozzle element 19, and it will be seen that the supporting block, such as the block member 28, and the nozzle element carried by it, such as member 19 of Figure 7, may be constructed in quantity as 40 units and may be assembled to low pressure nozzle members like the element 12 in any desired spacings and in any desired number. In Figures 4, 5 and 7, the connecting tubular conduits of the additional nozzle units 20—29 and 21—30 are indicated at 34 and 35, respectively, the three relatively small tubes extending upwardly within the tube element 12 to a control distributor generally indicated by the reference character 36 and being relatively small, being 50 preferably made of a metal like copper or bronze, they are also mechanically encased and housed by the relatively large heavy and strong tube member 12 and thus protected against mechanical injury, distortion or the like. In cross-section 55 they are relatively small as compared to the cross-sectional interior of the low pressure nozzle member 12 and the capacity of the latter is not detrimentally affected by their presence nor is the discharge flow of liquid from the mouth M of the low pressure nozzle member 12 materially affected as to its desired rate of flow and action, by the presence at or in the mouth M of the nozzle-mounting blocks 28, 29 and 30.

The control distributor 36, referring now to 65 Figures 4 and 5, comprises a block 37 of suitable metal provided with a main distributing channel 38 formed as by drilling a hole of substantial diameter from one end face 37^a toward the opposite end face 37^b, but falling short of the latter, the open end of the channel 38 being threaded as at 38^a to provide for the threaded connection thereto of the high pressure conduit 23 above mentioned.

We then arrange for the connection to the 70 distributing channel 38 of as many pipes or

tubes as there are high pressure nozzles, illustratively the three tubes 32, 34 and 35, but preferably in a manner to provide for the individual control of the volume and pressure of flow of liquid to each high pressure nozzle. Thus we may provide, as by drilling from the side face 37^c, three channels 37^d, 37^e and 37^f which intersect the distributing channel 38 at their inner ends and in their outer ends receive and have sweat-ed or soldered thereto the tubes 32, 34 and 35 which pass through suitably large holes H provided in the adjacent wall of the nozzle tube 12.

In assembly, the nozzle-carrying blocks, such as blocks 28, 29 and 30 of Figure 5, are joined to the lower ends of their respective tubes after the latter have been connected to the channels 37^d, 37^e and 37^f of the block 37, whence the nozzle-block-carrying ends of the tubes are snaked through the holes H which are large enough for that purpose and snaked downwardly within the nozzle tube 12, thus bringing the nozzle-carrying blocks into position to be received within the slots 25, 26 and 21, respectively, in the wall portion 17 and thus also bringing the face 37^c of the block 37 of the distributor 36 into alignment with the outer face of the tube element 12 to which it is secured as by welding, indicated at 40, and to the curvature of which the face 37^c is suitably conformed. Thereby also the holes H are closed off, and it will be seen that commingling of the liquids supplied to the mouth M of the low pressure nozzle and to the orifice channels 33 of the high pressure nozzles does not take place.

Suitable controllable valve means are provided, preferably one for each high pressure nozzle circuit and such control means we preferably assemble to or build into the above-described block 37, conveniently relating each to one of the channels 37^d, 37^e and 37^f. Such means may comprise valve structures generally indicated by the reference characters 41, 42 and 43 and preferably of identical construction. Thus, each may comprise a needle valve stem 44, preferably threaded and conveniently it is of the same diameter throughout its length and preferably slightly larger in diameter than the diameter of the drilled channels 37^d, 37^e and 37^f and they are threaded into holes 37^g, 37^h and 37ⁱ which respectively intersect the channels 37^d, 37^e and 37^f, being formed as by drilling from the face 37^k of the block 37 toward the opposite face to a depth sufficient to intersect the tube-connecting channels. Each valve member 44 may be provided with a handle or thumb grip 45 to facilitate setting by hand if desired, their threaded fit into the just-mentioned threaded holes is preferably relatively tight so as to be leakproof and self-locking, but a lock nut 46 may be provided for each and, if desired, a gasket of suitable material that is compressible and radially expandable under the compression of the lock nut may be employed to insure against leakage, particularly where the pressures dealt with are very high, or any other suitable form of stuffing box or packing gland may be employed.

Accordingly, the amount of liquid flowing to each high pressure nozzle and hence also the pressure effective upon the orifice channel of each nozzle may be set by adjustably positioning the valve structures 41, 42 and 43 to any such respective positions as may be desired between complete cut-off of the channels 37^d, 37^e and 37^f, as when the valve stems 44 are threaded inwardly to completely obstruct these channels, to maxi-

mum flow as when the valve stems are threaded outwardly to positions in which they do not materially obstruct the flow in the channels or materially reduce the cross-section thereof at the valving point therein.

In the high pressure pipe line 23, which may be provided with suitable valve controls such as the valve 47, we provide suitable means for supplying to the control distributor head 36 liquid under suitably high pressure, and such means may comprise a pump diagrammatically indicated at 48 in Figure 1, the pump being preferably of any suitable high pressure, relatively low volume, type. It may be driven by any suitable means not shown, such as a separate electric motor or from the main drive of the machine by which the grinding wheel G is driven at a suitable grinding surface speed. A wide range of pressure may be selected for the high pressure side of the system, depending upon various factors, such as the composition and action at the grinding line of the liquid to be employed, the character of grinding operation to be performed, and other factors later mentioned. For present purposes, pressures from about 20 pounds per square inch and higher, such as 100 pounds per square inch or over may be considered, and any suitable means may be provided for setting the pressure of the output of the pump 48 at the desired value—such as, for example, a by-pass pressure regulator diagrammatically indicated at 49.

In the pipe line 15, which also may be provided with suitable valve controls such as indicated at 51, suitable means are provided to supply the relatively large and high-volume tube nozzle 12 with large volume of liquid at preferably very low pressure—a pressure which is preferably only sufficient to achieve large-volume, low-pressure, and relatively low-velocity flow or movement of liquid out of the very large mouth M. For this purpose a suitable high-volume, low-pressure pump, diagrammatically indicated at 52, driven in any suitable manner—for example, like the drive of pump 48—may be provided, and for control of the flow out of the mouth M, valve 51 can suffice, for, as later described, variability as to volume or quantity of flow can suffice.

To give illustrative functioning and results of our invention, let it be assumed that the work-piece W is of steel and the grinding wheel G is of a structure, such as ceramically-bonded, suited or selected for operation upon the particular kind of steel of the workpiece W, and that the grinding wheel G is driven at its best-suited surface speed and the workpiece W is rotated at a correspondingly best-suited surface speed—all as measured or determined by heretofore known criteria or standards. In carrying out a preferred embodiment of our invention, we supply, simultaneously, to the low-pressure discharge nozzle 12 and to the high-pressure nozzles 19, 20, and 21, respectively, a suitable coolant liquid and a suitable promoting or active liquid,—illustratively, water for the former and oil for the latter,—utilizing, in the said embodiment, respective pressured therefor like those above mentioned, substantial commingling of the two being avoided by the arrangement of the respective nozzles relative to the work and grinding wheel and by other actions later described.

As appears better from Figures 4 and 7, the orifice channels 33 in the high-pressure nozzle or nozzles are directed so that the high-velocity and high-pressure streams of oil that they emit impinge, in the preferred arrangement, upon and

against the grinding wheel operative surface, in the illustration the peripheral surface P, at a point or points, preferably just somewhat in advance of the grinding line L. The angle of incidence of the high-pressure oil streams is preferably such that the oil stream makes an acute angle, indicated at A in Figure 4, with the grinding wheel surface, with the apex of the angle directed generally in the same direction as the direction of travel of the operative surface of the grinding wheel or, stated differently, the oil stream or streams are directed into the angularity formed between the surface of the work being ground and the advancing operative surface of the grinding wheel, but offset so as to strike the grinding wheel surface at a suitable point displaced from the grinding line L.

In Figure 4, the stream from high-pressure nozzle 19 is indicated at S¹ and the point where it strikes the grinding wheel surface P is indicated at I. The distance from point I to the grinding line L is variable, according to various factors, such as the pressure at which the oil is supplied to the high-pressure nozzle, and for purposes of illustration it may be on the order of $\frac{3}{8}$ of an inch or $\frac{1}{2}$ inch or so. The angle A is also variable and the desired effect, later described, may be achieved with a wide range of change of angle A; it is preferably an acute angle with its apex headed in the direction of travel of the operative surface of the grinding wheel, in order more effectively to spread over or cover the moving grinding wheel surface, between the point I and the grinding line L, with a substantial layer of oil, that action being aided by several factors, including the direction of movement of the grinding wheel surface P and the high velocity of travel of the oil in the impinging stream or streams. For the stream S¹ in Figure 4, this film of oil, of substantial thickness, is indicated at F¹, and it reaches from the point I to the grinding line L, and in Figure 6, is indicated at S¹ the cross-section of stream S¹ just before it strikes the grinding wheel surface P at the point I which will thus be seen to be not a geometric point devoid of dimension, but an area at least as large as the cross-section of the oil stream S¹ and usually substantially larger because of the spreading action that takes place as it actually strikes the grinding wheel surface.

The grinding wheel surface P, however, is moving downwardly, as viewed in Figures 1, 2, 4 and 6, at high velocity, illustratively at an appropriate grinding speed which may be on the order of 6,000 surface feet per minute, and as a result, aided by the angle A where the latter is an acute angle, the oil from the impinging stream S¹ is carried intact as a film of substantial thickness downwardly by the grinding wheel surface toward the grinding line L and in actual action it fans out or spreads or diverges downwardly and cross-wise of the wheel face P, to both sides of the point I of incidence. This spread, indicated in Figure 6 by the reference character R¹, is controllable and variable as is later described and illustratively may be on the order of about $\frac{3}{4}$ or $\frac{7}{8}$ of an inch.

Were the grinding wheel surface P to be of a width of about $\frac{3}{4}$ of an inch, it will thus be seen, a single high-velocity high-pressure stream or jet of liquid, such as the stream S¹ of Figure 6, if directed at the midpoint of the wheel surface, would suffice to give a spread R¹ sufficient to supply the grinding wheel surface, at and in advance of the grinding line L, with a unitary or intact layer-like body of liquid. Where the wheel face P is

wider, as in the illustration, such as to require three high-pressure streams or jets, they are appropriately distributed so that the downwardly and outwardly fanning or diverging layers F¹, F² and F³ (see Figure 6) overlap preferably well in advance of the grinding line L, thus to make sure that the entire face of the grinding wheel, as it moves at high velocity toward the grinding line L, is covered with a substantial thickness of liquid film.

Emerging from the mouth M of the large-volume, low-pressure nozzle 12 is a slow-moving substantially unbroken stream or column C of water; its head is small or slight, just sufficient to maintain a steady and copious flow, and in comparison to the energy in the high-pressure jets, the stream or column C is of very small or virtually immaterial energy content, and in relation to the high velocity of movement of the high-pressure streams S¹, S² and S³ with their diverging and high-velocity layers or films F¹, F² and F³ (see Figure 6), we, by the just-described relationships, make sure that the stream C interferes practically not at all with the above-described conformations of the high-velocity streams or jets and their high-velocity films or layers. The latter thus remain intact and substantially undisturbed and substantially free from material disruption by the slow-moving, but copious stream C, and thus the liquid substance, illustratively oil as above mentioned, that is supplied to the grinding machine through the high-pressure nozzle or nozzles is with certainty brought to the grinding line L, where its qualities and characteristics, later described, coact with the grain and bond of the grinding wheel and the material of the workpiece W to achieve grinding actions later described. This liquid substance, peculiarly adapted for facilitating high rate of cutting by the abrasive grains of the wheel is backed up (see Figure 4) by the large-volume, slow-moving liquid column C, which is preferably of water, a good heat-absorber, and which can fill the angle between the surface of the work piece W and the outer faces of the fanned-out layers F¹, F² and F³, and thus the liquid of the latter is not only fed to the grinding line at a low temperature (room temperature, for example) but also is prevented during the actual grinding at the grinding line L with its accompanying production of heat from being so raised in temperature as to diminish or vitiate its coaction with the grinding wheel. The liquid from the stream C spills to the right and left (see Figure 2) from the trough-like space above the grinding line L, spreads onto the grinding wheel below the grinding line L to withdraw heat from it, and also, from this lateral spilling-over, spreads onto the work piece W to withdraw heat from the latter, and if desired and according to the dimensions and setting of the parts, some of it can also be made to spill over the top of the work piece W as indicated at C¹. Thus the temperature of both grinding wheel and work piece can be dependably held down to a value, in spite of any increase in energy that may be manifested at the grinding line L in the form of heat because of the resultant increased capacity of the grinding wheel, at which the grinding liquid in the high-pressure streams and films or layers is best adapted to function and thus also burning with resultant deterioration, and evaporation of the grinding liquid and resultant waste thereof can be avoided; thus also the creation of obnoxious fumes can be avoided, ventilating or exhaust apparatus need not be employed, and

grinding operations can be made less hazardous to health.

It will be noted, by reference to Figure 4 for example, that, even if the grinding wheel itself becomes materially raised in temperature, such increased temperature is prevented from having material effect upon the grinding liquid supplied to its surface from the high-pressure nozzle or nozzles because that liquid, being backed up by the large-volume column or stream C of heat-absorbing liquid, is by the latter prevented from itself being raised in temperature, and the liquid of the column C, being in thermal contact with the film or layers F¹, F² and F³ of the grinding liquid, is thus capable also of withdrawing heat from the grinding wheel itself in advance of the grinding line L, thus further to resist undesired pre-heating of the high-pressure, high-velocity liquid from the grinding wheel itself.

It is probable that small or minute quantities of liquid from the column C become commingled at the grinding line with the liquid from the high-pressure nozzles, but such action is in substantial measure controllable and according to the nature of the work it can be beneficial to the actual grinding operation. Where, for example, it is desirable to avoid or minimize such commingling at the grinding line L, the pressure at which the liquid is supplied to the high-pressure nozzles may be increased as by correspondingly setting the pressure regulator 49, and thus the velocity of the streams S¹, S² and S³ may be made so materially greater than the velocity of the grinding wheel surface P that the fanned-out layers F¹, F² and F³ are thicker and move at increased velocity, thus more effectively to "nose out" the liquid from the column C against reaching the grinding line L in substantial quantity. The valve structures 41, 42 and 43 in the control distributors 36 may also be set or adjusted for this purpose.

Analogous effects may also be achieved by so adjusting the compound nozzle structure 11 or by setting the individual nozzle elements 19, 20 and 21, or both, to lessen the distance from the point of incidence I (see Figure 4) to the grinding line L, thus to diminish the chance of the liquid from the stream C from commingling with outer portions of the layers F¹, F² and F³. Also, the active fluid emerging from the nozzle elements 19, 20 and 21 may by such adjustment be made to impinge directly into the apex of the angle between the wheel face and the work surface, and still form an effective barrier against material entry of the coolant liquid into the region of grinding contact. According to circumstances also, the volume of flow of liquid in column C may be lessened as by the valve 51 (Figure 1) to better suit it to the barrier action of the active grinding liquid.

The pressure of the grinding liquid supplied to the grinding operation may be varied and even materially cut down or its direction of flow or shape of stream altered so long as it has the effect of a barrier to prevent material commingling with the liquid in stream C.

In carrying out our invention, because of the protective action of the high-volume, low-pressure liquid supplied through nozzle 12 upon the high-pressure, low-volume grinding liquid supplied through the nozzles, it is possible to use, over and over again, the liquids employed; if the low-pressure liquid employed is water, it may, of course, be freely replenished from any suitable source of supply, and in any case it may also be re-used, whatever form or composition it takes.

We prefer to catch the coolant and active liquids, after they have performed their functions, in any suitable sump or settling tank, generally indicated in Figure 1 at 54, in which some settling out of grit and other solid particles resulting from the grinding operation may take place. From such a sump 54, the commingling liquids, with such solid particles as are carried with them, may be passed, as by a conduit 55, to any suitable form of separating apparatus or system diagrammatically and generally indicated as a unit in Figure 1 by the reference character 56. In the separator 56 the solid particles are removed or separated out, and the two liquids separated from each other, and, as so separated, the high-volume, low-pressure liquid may be passed, as by the pipe 57, to the intake side of the pump 52, and the low-volume, high-pressure liquid passed, as by pipe 58, to the intake side of the pump 48.

20 In so far as certain features of our invention are concerned, the separator 56 may be of any suitable construction appropriate for the handling and suitable separation of the particular liquids employed; thus, it may effect separation by centrifugal action or, by way of further example, by settling out one of the liquids below the other because of their different specific gravities. However, according to certain other features of our invention, we are enabled to achieve 25 certain advantages and beneficial coactions by giving the separator system 56 a form later described in detail.

In Figure 2 is shown diagrammatically the apparatus of our invention applied to a grinding apparatus in which the workpiece W¹ is to have its external cylindrical surface ground throughout its axial extent, the apparatus being arranged as in any known manner to effect a relative traverse in axial direction between the work and the grinding wheel, thus to progress a selective depth of cut lengthwise of and throughout the axial extent of the workpiece W¹; the set-up of Figure 2 is thereby intended to illustrate or typify a grinding operation in which the grinding wheel operates by one of its available operative surfaces, illustratively the peripheral surface P. In such a set-up, the relative pressures of the two liquids, the settings of the nozzle elements either as a whole or individually as to the high-pressure nozzle elements 19, 20 and 21 may be as above described in connection particularly with Figures 4 and 6, the overlapping or joined fanned-out grinding liquid layers F¹, F² and F³ being controlled to insure coverage of the grinding wheel surface P along the length of the grinding line L and also in advance thereof, it being pointed out that the relative traverse between the grinding wheel and the workpiece W¹ has substantially no material detrimental effect, such as detrimental distortion, upon the film or layer of the one grinding liquid that is laid against and carried by the grinding wheel surface or upon the action and functioning of the stream or column C of the other liquid. Certain illustrative grinding performance figures, with a set-up like that just described in connection with Figure 2, are later hereinafter set forth.

As earlier above indicated, there are, however, grinding operations in which the grinding wheel 70 is called upon to operate by way of one or more operative surfaces in addition to its peripheral surface, such as operations where the two faces forming a corner of the wheel operate, thus imposing peculiarly severe conditions of performance upon the wheel structure, and to illustrate

such a grinding operation, we have in Figure 3 diagrammatically shown a set-up comprising the grinding wheel G and a work piece W² in the form of a crankshaft in which the crankpin CP is to be ground to cylindrical form of the right diameter and simultaneously the adjacent side faces 61 and 62 are to be ground plane at right angles to the axis of the crankpin CP, such work usually requiring a relatively sharp corner at the respective junctions between the faces 61 and 62 and the cylindrical surface of the crankpin CP. A typical limitation is that, at these corners, a fillet not to exceed a certain radius is permissible, such as a radius of $4/64$ of an inch. In Figure 3 the fillet is indicated at 63. The apparatus diagrammatically indicated in Figure 3 is of the kind in which the crankshaft W² is mounted in suitable supports (not shown) to rotate about the axis, indicated at 64, of the crankpin CP and in which suitable provision is made to effect relative movement between the grinding wheel G and the crankshaft W² to diminish the distance between their respective axes, thus to bring the side faces P¹ and P² into action, respectively, upon the work faces 61 and 62 and ultimately to bring the peripheral operative surface P into action on the surface of the crankpin CP, the grinding wheel G being trued so that its peripheral surface P is truly cylindrical and so that the side faces P¹ and P² are parallel to each other and spaced apart by a distance to grind the faces 61 and 62 not only parallel but also to the required spacing between them.

In such an operation, as the grinding wheel and work piece are brought into coaction, the mechanical burden upon the corners of the wheel is unusually heavy and severe, both during the in-feed, that is, as grinding of the side faces 61 and 62 proceeds, but also and more particularly as the grinding of the crank pin CP proceeds; the faster that one attempts to carry on this type of grinding operation, the more rapidly do the corners of the wheel wear and break down and the more frequently does the wheel have to have its peripheral face P trued off, thus to restore the corners, and thus the life of the wheel is greatly shortened. With our invention, however, we are enabled to achieve increased grinding production and to extend the life of the wheel.

For simplicity it may be assumed that the grinding wheel G of Figure 3 is of the same width of face as was assumed to be the case in Figures 2 and 6 and that, therefore, the same compound nozzle structure 11, embodying illustratively three high-pressure nozzles 19, 20 and 21, may be employed; the width of the laterally-flared lower end of the nozzle structure 12 (see Figure 2) can be less than the width of the peripheral face P of the grinding wheel, and, overhanging the latter in the manner shown in Figures 1 and 2, the structure 11 will be seen not to be in the way of the swing of the crank parts of the crank shaft W² as the latter is rotated about its axis 64.

For such a crankshaft grinding operation, and in view of the duty to be performed by the side faces P¹ and P² of the grinding wheel, it is preferred to better insure the supply of high-pressure grinding liquid to the region or regions where the side faces are performing their respective grinding operations, and in such case one or more adjustments or settings may be brought into action, either individually or in co-action.

For example, and referring to Figure 6, the

pressure or rate of flow in the streams S¹ and S³ emerging from the outermost nozzle elements 19 and 21, respectively, may be increased as by increasing the opening of the valve structures 41 and 43, respectively (Figures 4 and 5), and such action would have the effect of increasing the fanning-out or divergence of the films or layers F¹ and F³ and thereby causing more oil or other grinding liquid from the streams S¹ and S³ to be diverted laterally beyond the planes of the side faces P² and P¹, respectively, thus making more grinding liquid available for coaction with the crankshaft faces 61 and 62 (Figure 3) and the respective side faces of the wheel. In making such a setting, therefore, the pressure and velocity of jets or streams S¹ and S³ would be greater than those of stream S².

Or, assuming that, as earlier above described with respect to Figure 6, all of the rotationally adjustable orifice elements 19, 20 and 21, had initially been set so that their orifice channels 33 are parallel to each other, their downwardly inclined axes (see Figure 7) falling in parallel vertical planes, we may insure the greater supply of grinding liquid to the grinding operation at the side faces by rotationally shifting the setting of the outermost nozzle elements 19 and 21, in directions respectively clockwise and counter-clockwise as viewed in Figure 5, thus causing the points of incidence of the jets S¹ and S³ to become displaced more closely to the respective side edges of the grinding wheel face P, somewhat in the manner indicated in Figure 8 which, when compared with Figure 6, shows how, as a result, the axes or general lines of flow of the fanning-out layers F¹ and F² are thereby directed or inclined away from each other and respectively toward the faces 62 and 61 just above the line or arc of the peripheral face P of the wheel, thus flowing an ample supply of grinding liquid onto the surface being ground and also onto the side faces P² and P¹ of the grinding wheel itself. If, in making such an adjustment, the spread of an intervening stream, such as the spread F² of the jet S², is insufficient, the rate of flow or pressure, or both, in the pipe line supplying the intervening nozzle—in this case, nozzle element 20—may be increased, as by increasing the opening of the valve structure 42.

Or, of course, both adjustment of pressure and adjustment of angle of incidence of the various high-velocity jets may be effected to achieve the desired action and distribution. In a grinding operation like that of Figures 3 and 8, the high-pressure, high-velocity liquid is again backed up by the high-volume, low-pressure liquid of column C emerging from the mouth M of the nozzle 12, and, because of factors like those above described, commingling does not take place to any detrimental extent, and vastly increased grinding performance with correspondingly increased length of life, due to the greatly improved standing up of the wheel corners, are achieved—with respect to all of which some illustrative performance figures are later hereinafter set forth.

As above pointed out, the high specific heat of water, its ready availability and inexpensiveness, make it a preferred liquid to employ for the high-volume, low-pressure side of the system. For the active or grinding-promoting liquid usable in the low-volume, high-pressure side of the system, we prefer to employ an oil of which a wide variety and kinds are usable according to our invention. It is preferred that the active or grinding liquid and the coolant liquid be sub-

stantially insoluble one in the other, and a number of illustrations of usable oils may be set forth—all of them, with respect to water as the coolant liquid, meeting this preference. Oils, such as, mineral, animal, or vegetable oils, may be employed, preferably treated to embody ingredients, such as sulfur or chlorine compounds, to give them or to improve their action at the grinding line in promoting cutting by the abrasive grains. Oils of this nature may be loaded, in known manner, with suitable sulfur compounds or chlorine compounds, or both, such as, for example, sulfur chloride, and preferably they are suitably treated, in known manner, to utilize and have embodied therein animal or vegetable fats and usually, also, sulfur. For example, sulfur may be reacted with such fats and dissolved in a mineral oil base, giving what is very probably a colloid or colloidal solution; from such a compounded oil, maximum cutting or grinding benefits are achieved—benefits derived not only from the presence of the fat, but also from the presence of the sulfur. Mineral oils, without modification by such additional ingredients as sulfur, fat, or chlorine, are usable to advantage in our invention; some animal oils and some vegetable oils, when employed in our invention, show less advantage than other animal or vegetable oils and, hence, their selection as the active liquid in our system will, of course, be correspondingly influenced.

Most conveniently, and preferably, we employ so-called "grinding oils" of the "insoluble" type, many of which are available on the market and which are especially compounded for grinding operations. Some of them, by way of illustration of their compounding in so far as fats, sulfur, and like ingredients are concerned, contain about 20% fat and 2½% of active sulfur; others are free of sulfur content and contain chlorine and fatty matter, such as 0.3% chlorine and 14% fatty matter; some contain a sulfurized, fatty acid base and a free, fatty acid oil; others contain a sulfur-chloride base and a small or negligible amount of fat. Such ingredients may vary widely as to their nature and proportions; for example, another such oil contains 15% of fat and 3% of sulfur. Such oils and water are not mutually soluble, and the non-soluble grinding oils that we prefer to employ are those distinguishable from so-called soluble oils or pastes, or compounds which are intended to be and are, for grinding purposes, mixed with or dissolved in water, usually in a ratio on the order of 1 to 40, to be used in grinding operations when so mixed or dissolved with water. Illustrative grinding oils suitable for use in the high-pressure side of our system are available on the market by the following identifications: White & Bagley Co. No. 1729, Stuart Threadcut oil, Sinclair Wil Kut oil, Windsor No. 1 of F. E. Anderson Co., Windsor Gear Grinding oil No. 300 of F. E. Anderson Co., Stuart Grinding oil Super Kool 81X, International No. 156 Grinding oil, International No. 152, Grinding oil, E. F. Houghton & Co. Cutmax H-S, Houghton Stainless Thread Grinding oil, and others.

Employing such grinding oils in combination with water, according to our invention and in the manner above described, grinding performance tests, in comparison to performance data achieved by following heretofore known practices, show the achievement of unexpected and outstanding results. For example, considering the traverse grinding operation of the kind above described in connection with Figure 2, using a grinding wheel

of 20" diameter and 2" width of peripheral face, P., operating at 1150 R. P. M. upon a work piece, W, of hardened steel (Rockwell C51), of a diameter of 2½", driven at 90 R. P. M., with a rate of 5, relative traverse in axial direction between grinding wheel and work piece of 42" per minute, the following comparative data were obtained.

(a) Using White & Bagley No. 1729 grinding oil on the high-pressure side of our system with water on the low-pressure side, and taking a radial cut of ½ mil, which means an index feed of one mil (0.001") per pass or traverse for fifty traverses, measurements and observations indicated a wheel wear of 0.6 traverses to "die out," 15 profilometer readings of the surface finish at the beginning and at the end were, respectively, 11 and 12, and net power input to the grinding wheel was 2.6 kw. Utilizing a known commercially available soluble oil, dissolved or mixed with water 20 in the ratio of 1 to 40 and applied to the same grinding operation in accordance with heretofore known methods, the wheel wear was 2.0 mils (meaning reduction in wheel diameter) for fifty traverses at an index feed of 1 mil, eight passes. 25 were required to die out, initial and final profilometer readings were, respectively, 10 and 16, and net power input 4.0 kw.

(b) Repeating the two just-described comparative tests, but with an index feed of 2 mils 30 per traverse, and taking the average for four sets of comparative runs of 50 mils total index feed per run, the comparative figures are: When practicing our invention, wheel wear was 0.4 mils, eight die-out passes, initial and final profilometer 35 readings of 10 and 22, and net power input of 4.5 kw.; when following prior practice as described in preceding paragraph (a), the wheel wear was five times as great, namely, 1.9 mils, ten die-out passes, initial and final profilometer readings were 10 and 48, and power input was 6.5 kw.

Comparative results in a traverse set-up like that of Figure 2, but operating upon soft crank-shaft steel (Rockwell C20), with a wheel surface speed of 6200 feet per minute, a work speed of 90 R. P. M. for a work piece of 2½ inches in diameter and a rate of relative traverse between grinding wheel and work piece of 42" per minute, and, with a total index feed of 200 mils per run, were as follows:

(c) A run made according to our invention and using the liquids mentioned in above paragraph (a), with an index feed of 2 mils per traverse, the wheel wear was 1.0 mil, die-out passes were six, initial and final profilometer readings were 14 and 30, and power input 3.5 kw. By comparison, following known practice with the soluble oil solution described in paragraph (a), and again effecting an index feed of 2 mils per traverse, breakdown of the wheel face occurred at the 60 halfway mark of the run or at about after 100 mils of index feed; that would require re-truing in commercial practice but the run was continued to the intended 200 mil total index feed. At the end of the run the wheel wear was nine times as great, namely, 9.0 mils, it required fourteen die-out passes, initial and final profilometer readings were 11 and 50, and the power input almost double, being 6.0 kw.

(d) Repeating these comparative tests, but taking an index feed of 4 mils per traverse, the following comparative data were obtained: When grinding according to our invention, the wheel wear was 0.5 mil, six traverses were used to die out, initial and final profilometer readings were 12 and 55, and power input was 6.8 kw. When

grinding according to prior practices using the solution of soluble oil and water described in paragraph (a) above, breakdown of the wheel face occurred at about the halfway mark and hence after an index feed of 100 mils had been effected and the run was continued to the intended total index feed of 200 mils. The wheel wear was sixteen times as great, being 8.0 mils, the character of surface such that fourteen die-out passes were required, initial and final profilometer readings were 10 and 85, and the power input 8.5 kw.

In those runs described in paragraphs (c) and (d) above which were made in accordance with our invention, the grinding oil was applied by way of three jets or streams projected by three nozzle elements having nozzle channels of $\frac{1}{16}$ " diameter, the jets were spaced about $\frac{7}{8}$ " apart and centered in relation to the 2" width of grinding wheel face, oil pressure was 95 pounds per square inch, and the points of incidence of the jets upon the wheel surface about $\frac{3}{8}$ " above the grinding line L as viewed in Figure 6, and the rate of flow of high-volume low-pressure water in the stream C as in Figure 4 was about six gallons per minute. The same factors were present in the runs described in paragraphs (a) and (b) above. Also, the points of incidence of the high-pressure low-volume jets, in all of these runs, was just about $\frac{3}{8}$ of an inch above the grinding line and, referring to Figure 6, because the spread or fanning-out as at F¹, F² and F³, was appropriate to cover adequately the width of the grinding wheel face at the pressure employed, the nozzle elements 19, 20 and 21 were, in these runs, set so that their channel orifices 33 had a normal inclination, that is, their axes were in respective vertical planes parallel to each other as considered in Figure 5.

Since, in a set-up like that of Figure 2, a relative traverse in axial direction between the work W¹ and the grinding wheel G took place, as by traversing the work holder and the work W¹ back and forth in the direction of the arrow indicated on the work W¹ in Figure 2, and grinding took place during each traverse stroke, it will be seen that, relatively speaking, the left-hand edge of the grinding wheel face P becomes the leading edge on one stroke and the right-hand edge becomes the leading edge on the opposite stroke. We have found that, apparently because of the controls effected as above described, such as high pressure and high velocity of movement of the grinding liquid or oil onto and downwardly along the grinding wheel face P, the movement of the work-piece in the course of its traversing strokes or the movement of the surface of the workpiece in counterclockwise direction, as viewed in Figure 1, has no material or consequential detrimental action upon the oil covering the grinding wheel surface in advance of the grinding line as might be expected at the leading edge or end of the operative surface of the grinding wheel.

In any case, however, any such action can be easily avoided as by insuring that the spread (see Figure 6) effected by the high-pressure low-volume jet or jets is in excess of the width of the grinding wheel face. This can be effected, as will now be clear, by suitably inter-relating the various factors. Thus the pressure and hence velocity may be increased to increase the spread, or the end nozzle element or elements may be set or adjusted to change the direction or angle of incidence of the emitted jet or jets as was described in connection with Figure 8 and thereby

also give the moving film or layer of oil in advance of the grinding line a horizontal component opposing the direction of the relative traverse between the wheel and the workpiece.

- 5 Also, raising or lowering the high pressure low-volume jets relative to the grinding line may also be resorted to, or any combination of this with any of the other control factors already described.
- 10 Analysis of the comparative results and data set forth above in paragraphs (a), (b), (c) and (d) shows unprecedented accomplishment; for example, wheel wear is reduced to an unexpected extent and with it also is a practically commensurate reduction in the need and waste and time consumption in trueing the wheel; invariably, and for reasons we are unable to explain, reduction in power consumption in unexpected magnitude is achieved and, virtually paradoxically, the reduction increases with increase in grinding duty or work imposed upon the grinding wheels; moreover, superior finish on the workpiece is achieved and a given grinding operation is further speeded up in that "dieout" 20 passes or traverses are less and even with lesser dieout passes better profilometer readings are achieved.

But still more impressive are the actions and results achieved where the grinding wheel is called upon to perform by way of its corner or corners, as in a set-up like that of Figure 3. Comparative tests directed to the measurement of breaking down or wearing away of the corner or corners may now be considered.

- 30 In the data about to be set forth, in those runs where our invention was practiced, a single low-volume high-pressure nozzle element was employed, with its jet directed to strike the corner of the wheel at about $\frac{3}{8}$ of an inch above the grinding line, thus to cause the fanned-out or downwardly and outwardly diverging film or layer of oil to be divided substantially equally between the peripheral face of the wheel and a side face of the wheel, since both were to be operative upon 40 different surfaces of the workpiece; a narrow-faced grinding wheel (two inch width of peripheral face) was employed to function by way of only one of its corners, in order to simplify comparative tests and avoid possible complication by 45 having to consider what happens to both corners. In Figure 9, we have schematically indicated that grinding wheel G, operating by its peripheral face P and its side face P¹ and at S⁴ we have indicated the point or area of incidence of the low-volume 50 high-pressure stream or jet; that point or area is intersected by the corner of the wheel formed by the intersection of the trued faces P and P¹, and the angle of incidence is chosen so that the fanned-out layer portion F⁴ of grinding liquid 55 that is deflected by and onto the peripheral face P has a spread R⁴ about equal to the width of the surface P, while the fanned-out layer portion F⁴ that is deflected by and onto the side face P¹ has a spread R⁵ at least equal to the radial dimension 60 of the workpiece surface which it is to grind. That radial dimension, in the tests was on the order of $\frac{3}{8}$ of an inch. In Figure 10, the test workpiece is indicated at W³, it has a cylindrical portion 67, comparable to the crank pin CP of 65 Figure 3, which the face P is to grind, and it has an annular face 68 at right angles to the axis 69 of the workpiece W³ which is to be ground by the side face P¹ and which hence is comparable to the face 61 of the crankshaft workpiece of 70 Figure 3.

The grinding wheel faces P and P' are trued at right angles to each other with the plane of the face P' at right angles to the axis of the grinding wheel and the apparatus is constructed in any known manner, as above noted and as indicated by the arrows in Figure 10, to effect relative movement between the wheel and the work carrier and hence the workpiece in a direction at right angles to the axis 69 of the workpiece and toward or away from the latter. Accordingly, at the beginning of the grinding step and with the workpiece W^3 rotated at suitable speed and in suitable direction, the corner of the grinding wheel G first comes into grinding action upon the workpiece W^3 as the relative approaching movement between the wheel and the workpiece is effected, becoming operative by way of a narrow marginal portion of the peripheral face P (to the extent of the depth of cut or amount of metal to be removed at the face 68 of the workpiece) and also by way of the side face P' , until the entire width of the peripheral face P engages the cylindrical portion 67 of the workpiece whence the grinding of the latter is continued to the desired extent, for example, until the desired diameter of part 67 is arrived at. The grinding-work burden imposed upon the corner of the wheel is, it will be seen, very severe and in a grinding operation like the set-up in Figure 3, such a burden is imposed upon both corners. If the rate of relative approaching movement is too rapid, the corner breaks down or wears too rapidly, becoming out of shape or irregular or rounded over at a progressively increasing radius; these effects can become multiplied if the axial dimension of material being removed along the line of the face 68 is increased, the tendency here being to more rapidly increase the radius of rounding off of the corner. These actions singly or in combination thus cause the production of a fillet at 63 that is of an excessive radius or of greater radius than permissible. To effect correction in order to get the fillet within permissible limits, the grinding wheel face P is trued off to restore the corner to sharpness. If the effort is made to avoid frequent trueing which wastes the wheel and reduces its useful life, such effort has to be directed to taking lighter and more numerous cuts and to effecting lower rate of relative feeding movement, thus prolonging the grinding operation and slowing up production.

In the comparative corner-grinding tests, the grinding wheel is operated at a surface speed of about 6,200 feet per minute, the workpiece W was rotated, where the diameter of the part 67 was on the order of 2 inches and that of the larger-diametered part on the order of 3 inches, at 76 R. P. M., pressure of grinding fluid or oil as in the single jet S^4 of Figures 9 and 10 was on the order of 95 pounds per square inch accompanied by a large-volume low-pressure column or flow of water at the rate of 2.5 gallons per minute, and the material of the workpiece was the same for all tests, being so-called soft crankshaft steel; also nozzle elements of different sizes of orifice channels, thus to change the volume of flow of the high-pressure low-volume liquid were employed, all as noted below. Corner wear was determined by a radius or fillet gauge, to determine the radius of the fillet at 63 in Figure 10 in 64ths of an inch.

(e) Tests were first made according to heretofore known methods, utilizing the same soluble

oil, dissolved or mixed with water in the ratio of about 1 to 40, that was used in the comparative tests in paragraphs (a), (b), (c) and (d) above. Radius of the fillet (in sixty-fourths of an inch), after the first cut, was 4.0, and after the fifteenth cut was 10.5, showing that the corner of the wheel wore off by an increase in the radius of the corner from $\frac{1}{4}$ " to $10\frac{5}{64}$ ", a net increase of 6.5 sixty-fourths. Net power input was 1.3 kw.

10 These data are the averages for several runs of the just-mentioned known commercially available soluble oil which, based upon other factors and tests, may be said to be the best or better than average, in performance of compounds of this nature, and for these latter reasons was selected as a standard of comparison against which to gauge performance data when grinding according to our invention, of which the results and data of several tests are noted below.

(f) Using White & Bagley No. 1729 Grinding oil on the high-pressure side of our system and applied in a single stream S^4 (see Figure 9) impinging upon the corner as above described from a high-pressure nozzle having a channel orifice of a diameter of 76 mils, with water employed on the low-pressure side, fillet radius at 63 after the first cut was 2.9, and after the 15th cut was 5.2, with power input of 1.0 kw.; corner wear, in increase of radius, was only 2.3 sixty-fourths. Repeating this test with a slightly different grinding wheel structure or grade, fillet radius after the first cut was 3.9, after the fifteenth cut was 6.4, and power input was 0.8 kw.; corner radius increased only 2.5 sixty-fourths.

(g) This test, repeated with a lesser volume of grinding liquid in that a nozzle of orifice channel of 40 mils diameter was employed, showed that fillet radius as a result of the first cut was 2.9 and after the fifteenth cut was 5.5, with average power input of 1.0; corner radius increase was only 2.6 sixty-fourths.

(h) Repeating the last-mentioned test, but using on the high-pressure side of the system Stuart Threadcut oil, fillet radius after the first cut was 3.5 and after the fifteenth cut was 5.9, and average power input 1.0 kw.; wheel corner radius increased only 2.4 sixty-fourths.

(i) Using the above-mentioned Windsor No. 1 oil and a 76-mil nozzle, fillet radius after the first cut was 3.9, after the fifteenth cut was 6.8, and average power input was 1.0 kw.; wheel corner radius increase was 2.9.

(j) Repeating this test with the above-mentioned Windsor No. 300 oil on the high-pressure side of the system, fillet radius after the first cut was 4.9, after the fifteenth cut was 7.2, and power input was 0.8 kw.; wheel corner radius increased 2.3.

(k) Repeating, but with International No. 156 oil on the high-pressure side, fillet radius after the first cut was 3.5, after the fifteenth cut was 5.9, and average power input 1.0 kw.; wheel corner radius increased 2.4.

(l) Repeating with International No. 152 oil, fillet radius after the first cut was 3.5, on the fifteenth cut was 6.2, and average power input was 1.0 kw.; wheel corner radius increased 2.7.

(m) Repeating with the above-mentioned Houghton Stainless oil on the high-pressure side, fillet radius after the first cut was 3.5, after the fifteenth cut was 5.4, and power input was 0.8 kw.

In test (e) the wheel corner wear or increase in radius at the corner will be seen to be at the rate of 6.5 sixty-fourths for 14 cuts and may be said to be the optimum or best performance

according to best heretofore known methods, materials and practices; that took place at a power input to the grinding wheel or machine of 1.3 kw. In tests (f) to (m) of performance achieved by our invention, power input is invariably reduced on the order of 25%, and the rate of corner wear averages 2.4 per 14 cuts, the lowest corner wear figure being 1.9 and the highest being 2.9. The rate of corner break-down or wear is thus seen to be reduced in the ratio of about 6.5 to 2.4; the need to true the wheel, when using our invention, may thus be said to occur only $24/65$ as often as according to most favorable heretofore-known practices; or, generally speaking, the grinding wheel, once trued, when practicing our invention, will operate $65/24$ as long as the same wheel will operate according to best heretofore-known practices. This relation is, however, shown by test to be non-linear and the need for truing is reduced to something like $1/4$ as often, or the wheel, once trued, will operate four times as long. At the same time, material savings in power are accomplished, not to mention increased production, in that stoppages of work required for wheel truing are reduced. Incidentally, these data are of interest also when compared to performing the same grinding operation by using only water; one such test (n) gave a fillet radius or breakdown after the first cut of 6.5 and after the fifteenth cut of 17.0, and note the vast increase in power input, which was 1.8 kw.; here corner wear was at the rate of 10.5 per fourteen cuts.

As earlier above noted, our invention is applicable to other forms of grinding operations than those indicated in Figures 2, 3, 4, 6, 8, 9 and 10, and an illustration of another form of grinding is surface grinding, diagrammatically indicated in Figures 11 and 12, in which the grinding wheel G operates upon a work piece W⁴, which is suitably supported on a bed or table 71 arranged in any suitable way, as in typical surface grinding machines, to be moved or traversed back and forth (to the right and left in Figure 1, as indicated by the arrow 72) in reversible strokes of suitable length to traverse the upper face of the work piece W⁴ in successive strokes relative to the grinding wheel, the table 71 being provided with any suitable means, also usual in surface grinding machines, to give the table 71 and, hence, the workpiece W⁴ carried by it a suitable cross-feed (to the right or left in Figure 12, as indicated by the arrow 13), usually step by step and suitably timed with relation to the traversing strokes of the table 71. Illustratively, the apparatus may be operated so that the grinding wheel operates to grind the surface of the workpiece W⁴ on each stroke to the left and to the right, as seen in Figure 11, and the cross-feed indicated in Figure 12 may take place, or its increment of feed completed, at the end of each stroke of the table 71.

The active liquid and the coolant may be applied in various ways or combinations, utilizing both angular spaces between the grinding wheel and the work that are present, respectively, to the right and to the left of the grinding line L, as viewed in Figure 11. For example, the grinding oil may be directed to the grinding line in a stream or streams from the left in Figure 1, and the liquid coolant from the right, or vice versa; or the grinding oil may be directed from either side alone, and the coolant liquid applied to the workpiece W⁴ on both sides; or, by suitable table-controlled valves, the grinding oil and cool-

ant liquid applied alternately at the two angular spaces in synchronism with the working strokes of the table 71; or the liquid coolant always applied at both angular spaces, and the grinding oil, under the control of suitable table-actuated valves, applied alternately at the two angular spaces in synchronism with the working strokes of the table 71. All such arrangements give superior results over prior practice, and the last-mentioned one is preferred because maximum coolant liquid is continuously applied to the work-piece to withdraw generated heat and a minimum active liquid is used, and, hence, a lesser burden is imposed upon the separating apparatus or system 56.

In Figure 11 is diagrammatically shown the setup for carrying out this last-mentioned preferred arrangement. Thus, two nozzle devices 11 are employed and supported in any suitable way, as from the grinding wheel guard (not shown), to direct the liquids they discharge into the angular spaces, respectively, to the left and to the right of the grinding line L. The large-volume nozzles 12 are connected, by conduits 15^a and 15^b, to the conduit 15 of the coolant liquid circuit, and preferably valves 75 and 76 are provided in each of the pipes 15^a and 15^b, so that the rate of flow of coolant liquid may be set or controlled for each nozzle device 11. The distributor blocks 36 of the nozzle devices are connected, by pipes 23^a and 23^b, to the conduit 23, but, through a two-way valve 77, provided with an upstanding actuator or control arm 78, positioned in the path of movement of spaced blocks 80 and 81 adjustably secured to the table 71 and so positioned that at the end of each stroke of the table one of these blocks engages and turns the valve lever 78 to cut off the flow of active liquid to the high-pressure nozzle or nozzles of one of the discharge devices and to connect the high-pressure nozzle or nozzles of the other discharge devices 11 to the grinding oil supply line 23.

With such an arrangement, therefore—and assuming that the grinding wheel G is driven in clockwise direction, as indicated by the arrow—if the table 71 is moving to the right, coolant liquid is emerging from the mouths M of the two low-pressure nozzles 12, spread substantially uniformly over the surface of the workpiece W⁴, from which it runs off, carrying with it absorbed heat and thus preventing rise in temperature of the workpiece, and during this stroke toward the right, valve 77 is in a position to cut off the flow of active liquid in the pipe 23^a and to maintain flow of a grinding oil, through pipe 23^b, to the nozzle or nozzles of the right-hand nozzle device 11, that condition continuing until valve-operating block 80 trips the valve lever 78, whence the flow of grinding oil to the right-hand nozzle discharge device 11 is stopped and the flow of grinding oil to the left-hand discharge device 11 commenced. This changeover occurs just about at the end of the stroke of table 71 to the right and conditions the flow of grinding oil for the reverse or leftward stroke of the table 71, whence the valve-actuating block 81, at the end or reversal of the leftward stroke, effects a resetting of the valve 77, as will now be clear. The low-volume, grinding-promoting liquid is thus always supplied to the grinding line at what may be termed the leading side thereof, and maximum heat withdrawal may be effected by maintaining continuous flow of the high-volume, low-pressure coolant

liquid to the work on both the leading and trailing sides of the grinding line.

If it is desired to alternately discharge coolant liquid onto the workpiece at the leading and trailing sides of the grinding line, a two-way valve 83—which may be arranged, as by an operating lever 84, also to be actuated by table stops 80^a and 81^a—may be interposed between the main conduit 15 and the branch conduits 15^a and 15^b which lead to discharge devices 11, as is shown in Figure 13.

With such arrangement various combinations of control of coolant liquid and grinding liquid may be carried out, some of which are indicated above; for example, the two-way valves may be so constructed that they have a mid-position in which the liquid is passed to both branch pipes so that, when automatic actuation of either or both of them is not desired, the valve-actuating blocks on the table may be removed or spaced apart more, and the two-way valve manually set for discharge into only one of the branch pipes or for discharge to both branch pipes.

For surface grinding, advantages and superiority of results comparable to those earlier above set forth in connection with cylindrical grinding, are achieved. Moreover, a substantial range of change of relative conditions between grinding wheel workpiece and the two liquids applied thereto is possible, while retaining, in general, the unique advantages and results achievable by the invention, some of which are earlier above set forth in detail. For example, the point or points at which the grinding liquid is applied may be subject to some variation. Thus, good results are achievable if the grinding oil, with a relatively narrow grinding wheel face, is applied substantially at the corners of the wheel, as at S³ and S¹ in Figure 8, the narrowness of the wheel face not necessitating an intermediate stream or streams of grinding oil. In other words, with a narrower wheel, a stream as at S² in Figure 8 can be eliminated. On the other hand, a single stream, directed substantially at the mid-point of a narrow-faced grinding wheel, permitting adequate spread of the active liquid throughout the transverse extent of the grinding line L, has also been found to give good results. Moreover, under some circumstances, the active liquid need not be directed against or applied directly to the grinding wheel face, and this may be carried out with greater facility in surface grinding where, for example, the active liquid, particularly at the right of the grinding line L in Figures 11 and 13, with the grinding wheel turning in clockwise direction, may be permitted to discharge onto the surface of the workpiece W⁴ just to the right of the grinding line L. This may also be done at very low pressure of discharge or at very low velocity, if the windage caused by the grinding wheel aids in drawing the grinding oil into the apex of the angle and to the grinding line while, also, relatively large-volume coolant liquid emerging from the coaxing large nozzle 12 contributes to the action of virtually pushing or flowing grinding oil discharged onto the surface of the workpiece W⁴ in a direction toward the grinding line L. Because principally of windage effects in an opposing direction, the grinding oil discharged to the left of the grinding line L in Figures 11 and 13, is preferably discharged, if onto the workpiece W⁴, at a sufficiently high pressure or velocity to get it to the grinding line L in opposition to such windage effects. It may, however, also be directed to both the grinding wheel face and the surface of the

workpiece, or onto either of them alone, as will now be clear, and its velocity of application or the pressure at which it is supplied to the discharge orifices or nozzle, may vary considerably, depending upon physical or mechanical factors present in the particular grinding machine arrangement, the principal consideration here being that the grinding oil be gotten to the grinding line as little commingled with coolant liquid or water as possible, and it will thus be seen that circumstances can exist to bring this about without having to subject the grinding-promoting liquid to substantial pressures or to high velocity. The rate of supply of the active liquid to the grinding line is such that, in quantity, it is supplied to or present at the grinding line large enough materially to promote and aid the cutting and grinding action, and the coolant liquid should be supplied at a rate commensurate with the grinding duty being performed and, hence, the rate of heat production, so that the heat produced is removed without substantial rise in temperature of the grinding wheel (considered from the viewpoint of grinding wheel operating temperature) so that, also, the grinding oil can operate most efficiently—that is, at relatively low temperature—and the workpiece itself is prevented from such rise in temperature as may be dictated by the permissible tolerances or by such other factors as facility of manual handling.

At the grinding line it is possible that commingling of some of the grinding oil and of small amounts of coolant liquid take place. The relatively large quantity of coolant liquid and relatively small quantity of active liquid, applied to the grinding wheel and the workpiece, are, as earlier above noted, preferably caught, as in the pan 54 of the machine, whence they are passed onto the separator 56 in a more or less mixed state, but, being insoluble one in the other, the liquid that passes onto the separator system 56 is essentially a mechanical mixture. Carried with it is so-called swarf, which comprises the small particles of the material ground off of the workpiece and the small particles of the grinding wheel composition, including fragmentary abrasive grains, etc., etc. The swarf settles out mechanically relatively easily, but, in order to achieve certain additional coactions and advantages, we prefer to separate out the active liquid or oil constituent from the coolant liquid by the aid of heat, and then, after suitable treatment, to return the separated active liquid and coolant liquid to the grinding wheel and work, respectively, and in Fig. 14 is shown diagrammatically an illustrative and preferred form which the separator 56 of Fig. 1 may be given in order to achieve additional coactions and advantages.

In Fig. 14 the commingled or mixed grinding oil and water are received from the collecting pan of the grinding machine by way of the pipe 55, as already above described, the mixed liquids carrying with them a certain amount of swarf; all of this is preferably discharged into one end of a relatively long and wide trough 86, arranged at a slight incline (downwardly toward the right in Fig. 14) so that the mixed liquids from the machine can flow relatively slowly and at low or shallow depth throughout the substantial length of the trough, illustratively about six feet in length.

The discharge end of the trough 86 overlies one end of a relatively large-capacity tank 87; the tank, illustratively, may be of a capacity on

the order of 200 gallons, and the mixed liquids are discharged into one end of the tank (the right-hand end in Fig. 14) and, if desired, suitable screen-like filtering means 89 may be employed to mechanically separate such of the swarf as might be carried along with the discharge from the trough 86. The tank 87, which is preferably substantially elongated in a horizontal direction as seen in Fig. 14, may be provided with a baffle or partition 90 at the receiving end thereof, thus to provide a receiving chamber 91 into which the discharge from the trough 86 impinges. From the receiving chamber 91 the mixed liquids pass over the top edge of the partition or baffle 90 into an intermediate chamber 92 of substantial capacity in relation to the rate of flow of liquids in the system, so that the mixed liquids in the chamber 92 are relatively undisturbed or quiescent, quiescence being aided if desired by intermediate baffles as indicated; the baffle or partition 90 prevents any turbulence due to inflow of mixed liquids from the trough 86 from unduly agitating the liquids in the chamber 92, the transfer of mixed liquids over the top edge of the partition 90 taking place with little intensity of flow because of the appropriateness of the length of the baffle 90 in relation to the rate of movement of liquid in the system. In the receiving chamber 91, substantial settling out of swarf takes place so that mixed liquids transferring over the baffle 90 into the intermediate chamber 92 contain less solid matter or particles.

In the intermediate chamber 92, the left-hand wall of which is in the form of a baffle or partition 93 that is of lower height than the partition 90, the relatively large body of mixed liquids is, as above noted, relatively quiescent and a separation takes place, the water moving downwardly and the grinding oil moving upwardly so that, with the level of the liquid in chamber 92 being about as indicated by the broken line 95, a more or less well-defined horizontal plane of demarcation, as indicated by the broken line 97, comes into being and continues as the flow of mixed liquids into the chamber 92 and withdrawal therefrom of the separated liquids continues. There is, thus, in the chamber 92 a relatively deep layer 98 of water underlying a relatively shallow layer 99 that is principally of grinding oil, but contains a small quantity of entrapped water and also a small quantity of oil-water emulsion, the emulsifying having taken place as a result of the mechanical action at the grinding line upon some of the oil and such small quantities of water as may have gotten to the grinding line. The layer 98 is of materially greater depth than that of the layer 99, being, roughly, in the ratio of the rate at which the coolant liquid is supplied to the grinding apparatus to the rate at which the active or promoting liquid is supplied thereto. This ratio is relatively high and, hence, there is a substantial vertical distance in the intermediate chamber 92 throughout which the lower specific gravity of the grinding liquid can be made effective to bring the particles of grinding liquid upwardly away from the bottom of the chamber and into the upper layer 99. The coolant, therefore, is practically clear water adjacent the bottom of the chamber 92 and, hence, we prefer to withdraw it at this point for supply to the grinding apparatus. Thus, a conduit 100 connects through the bottom wall of the intermediate chamber 92 so that the separated coolant liquid may be withdrawn and sup-

plied to the conduit 57 (see also Fig. 1) to be led to the grinding apparatus, as by way of the pump 52, conduit 15, and discharge nozzle 12 above described.

The liquid that spills over the left end wall or baffle 93 of the chamber 92—largely oil, with some oil-water emulsion—enters what may be termed a collecting chamber 102 at the left end of the tank 87, and this chamber 102 is also preferably of substantial capacity so that some separation by gravity may continue to take place in the mass of liquid collected therein, the water, and any entrained solid particles that may accompany it, going to the bottom and settling out in a bottom layer, the amount of water in the liquid discharged into collecting chamber 102 is, however, relatively small and the separated water may be drained from the bottom from time to time in any suitable way, as by a drainage conduit 103 provided with a valve 104.

From a suitable point well above the maximum depth of separated water in the collecting chamber 102, the grinding oil, with the oil and water emulsion and now a still lesser amount of water, is withdrawn, as by a conduit 106, and passed through a heat-exchange device in the form of a heater 107 of any suitable or desired construction appropriate to substantially raise the temperature of the liquid appropriate to effect final separation of the oil, water and oil emulsion, and water into a substantially clear oil component and a substantially clear water component. A suitable temperature for this purpose may be on the order of from 160 degrees to 200 degrees F., and, so heated, the liquid passes, by way of conduit 109, to a tank 110, conveniently called the "hot tank." Hot tank 110 is preferably of relatively large capacity in relation to the rate of flow of active liquid in the system and, illustratively, may have a capacity on the order of 30 gallons. The high-temperature mix enters the tank 110 at a point about midway between its top and bottom, and in the tank the liquid mix is sufficiently quiescent so that, under the effects of the heat, the oil separates out, going to the top, the water going to the bottom. The water and oil emulsion is broken down and separated into its components of oil and water, and this action, under the effects of the heat, may be accelerated or aided, if desired, by the addition of small quantities of compounds such as alum, in known manner, for breaking down oil and water emulsions; such additions may be effected in any suitable manner, as by initially charging therewith the quantity of water with which the circulating and separating system is initially supplied.

The heating is of advantage, particularly with the more viscous grinding-promoting liquids, in that it increases their fluidity and, in the hot tank 110, thus accelerates the release of particles of swarf which by their own weight move down to the bottom of the tank 110 from which they may from time to time or otherwise be removed in any suitable manner, a drain and valve indicated at 125 being provided for such purpose, if desired, or for purposes of draining of the tank when necessary in cleaning the system.

On the other hand, we may operate our system without the application of heat, in which case the heater 107 is suitably constructed so that its heating action may be cut out; thus it may embody an electric heating unit 108 controlled as by a switch 105 by which it may be cut off from its source of energy. In such case it is desirable

to use additions such as alum above mentioned to aid in breaking down the emulsions in the tank 110. Separation of residue swarf can continue in the tank 110 or other means later mentioned may also be utilized to aid in finally separating out the residue swarf.

From a point in or near the bottom of the hot tank 110 a conduit 111 withdraws the separated water from the bottom layer in the tank, and such separated water may be returned to the system at any suitable point; being relatively small in volume and hence in rate of flow, it may be returned to the receiving chamber 91 of the main separating tank 87, as is indicated in Figure 14, or if desired it may be bled into the conduit 100 by way of a cross-conduit 112 having therein a check valve 112a, thus adding the separated coolant to the previously separated coolant moving in conduit 100 from the intermediate chamber 92 of the tank 87.

From an upper point in the tank 110 a conduit 113 is connected to withdraw the separated active liquid or oil, whence it is ultimately passed through a heat-exchange device 114. Preferably a suitable filtering means indicated at 115 is provided to keep the active liquid flowing out of tank 110 by way of pipe 113 as free of residue swarf as possible, and this filtering means 115 is preferably employed both when the liquid is heated in the heater 107 and when the heater is not made effective. The heat exchange device 114 may be in the form of a cooler of any suitable or desired construction appropriate to withdraw heat from the separated oil, not only the heat which the oil gained in the heat exchanger 107 if the latter is made effective but also heat which it may have gained at the grinding line or from commingling with the coolant liquid as it commingles with the latter in the grinding machine or the collecting pan of the latter, it being noted that the coolant liquid is raised somewhat in temperature as a result of its heat-absorbing action upon the work piece. The cooler 114 which may, for example, be a mechanical refrigerating unit, reduces the temperature of the oil to any amount desired and suitable, and this may be to a temperature materially below room temperature, if desired; and the oil, passed on to the grinding machine from the cooler 114, by way of the conduit 58 (Fig. 14 and Fig. 1), and conduit 23 and the nozzles 19, can thus be supplied at the grinding line at substantially constant temperature—and, moreover, at a reduced temperature—so that its capacity for absorbing heat energy dissipated at the grinding line is materially enhanced.

At the same time it is preferred to abstract heat from the separated coolant liquid before it is returned to the grinding apparatus, and heat-absorbing devices, or cooler 114, may be arranged to effect cooling of the water after it is withdrawn from the intermediate chamber 92 and before it is supplied to the distributing conduit 57 as indicated in Fig. 14.

Thus, the heat taken up by the coolant liquid in the grinding apparatus and abstracted from the workpiece may be removed and the coolant liquid returned to the grinding apparatus at a constant temperature, which may be any suitable temperature, such as at or below room temperature, and thus its capacity for heat absorption from the workpiece increased or maintained constant, or both. With similar control, as above mentioned, of the temperature of the active liquid uniformity of temperature conditions in the grinding apparatus during grinding operations may

be maintained throughout long, continued, successive grinding operations upon successive work-pieces, and thus it is made possible to work dependably within close tolerances in the quantity 5 production of workpieces or parts unaffected in any detrimental way by heretofore uncontrollable variables, particularly as to temperature conditions of operation.

We, therefore, preferably provide for the automatic 10 temperature control of the active liquid and the coolant liquid supplied to the grinding wheel and workpiece, and, by way of example, the cooler 114 may comprise two thermally-segregated coolers 114^a and 114^b, thermally insulated from each other, as by a suitable insulating barrier 114^c. Cooler 114^a may comprise a coil 113^a through which the oil passes as supplied by the pipe 113, and cooler 114^b may comprise a coil 100^a through which passes the water supplied by the pipe 100. Any suitable means, indicated at 116, may be provided to supply to the coolers 114^a and 114^b any suitable low-temperature fluid—such as brine or evaporatable refrigerant, such as is employed in mechanical refrigerants—through conduits 117 and 118, respectively, with return-flow conduits 119 and 120, respectively, preferably by suitable means responsive to the respective temperatures of the oil in pipe 58 and the coolant liquid in pipe 57. Thus, for example, a suitable temperature-responsive element 121 in the pipe-line 58 can be provided to control a valve 122 in the pipe 117, and a temperature-responsive device 123 in the pipe-line 57 can control a valve 124 in the pipe 118; these devices may be of any known or suitable construction, and the rate of supply of refrigerant or coolant fluid to the heat abstractors 114^a and 114^b may thus be controlled to give substantial constancy of temperature, at any desired equal or different levels for the active liquid and the coolant liquid as may be desired.

It will thus be seen that there has been provided in this invention a method and apparatus in which the various objects above noted together with many thoroughly practical advantages are successfully achieved. The method and apparatus will be seen to be of wide adaptability to various kinds or types of grinding operations, some of which are above mentioned by way of illustration, and for any particular grinding operation controls 45 of various variables are provided so that the method and apparatus may be readily accommodated to the requirements of any particular grinding operation. Thus, for example, the active fluid may be brought to the region of grinding contact 50 between the grinding wheel and the work piece, sometimes at high pressure and high velocity and at other times under widely differing conditions, but always in such coaction with the high volume coolant liquid and with related factors such as 55 character of the work piece, wheel windage, or the like as will achieve at the grinding line or region of grinding contact appropriate absence of substantial commingling of the two liquids; other controls of variable factors for such purposes as have been mentioned may also include, as is clear in view of the foregoing, adjustment or predetermination of angles of incidence of the various streams of liquids employed not only relative to each other but also relative to the grinding 60 wheel and the work piece. For example, rotational setting of such nozzle elements as the element 19 of Figure 7 or replacement thereof in its mounting by a nozzle element whose discharge channel 33 has a different angular relation to the axis of the element 19 can effect ap-

propriate control of the angle or angles of incidence of the active fluid relative to the discharge of the high volume coolant liquid from the mouth M; such settings may also be employed in relation to the setting of the nozzle device 11 of Figures 1, 11 and 13 as a unit relative to the grinding wheel and work piece, and for this purpose any suitable form of universally adjustable mounting or support therefor, diagrammatically indicated in the drawings at X, may be employed, the various conduits having suitable flexible portions to facilitate such adjustments. Thus in the drawings the nozzle devices 11 may be raised or lowered or their angle of tilt, as about an axis normal to the plane of Figures 1, 11 and 13, may be varied at will.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. The steps in a method of performing a grinding operation upon a work piece which comprise supplying separately to the place of grinding contact of the grinding wheel with the work piece and to the work piece an active grinding-promoting liquid and a coolant liquid respectively for promoting grinding action by the grinding wheel and for abstracting heat produced by the grinding operation respectively, said two liquids being mutually insoluble and being of different specific gravities, subjecting the resultant swarf-containing mixture of active liquid and coolant liquid and emulsions thereof to separating treatments which include separating out at least some of the swarf, utilizing the difference in specific gravities of the two liquids to effect separation of a major portion of the liquid coolant for re-supply thereof to the work piece, heating the remainder of the mixture to break down emulsified portions thereof and to separate out the active liquid and to increase the fluidity of the mixture to separate out the swarf carried by it, abstracting heat from the separated active liquid to lower its temperature, and re-supplying the separated coolant liquid and lower-temperature active liquid to the work piece and place of grinding contact respectively.

2. The steps in a method of performing a grinding operation upon a work piece which comprise supplying separately to the place of grinding contact of the grinding wheel with the work piece and to the work piece an active grinding-promoting liquid and a coolant liquid respectively for promoting grinding action by the grinding wheel and for abstracting heat produced by the grinding operation respectively, said two liquids being mutually insoluble, collecting the mixture of commingled active liquid and coolant liquid and emulsions thereof produced at the place of grinding, treating the mixture and emulsion with the aid of heat to separate out the active liquid from the coolant liquid, withdrawing heat from the separated liquids, and re-supplying them separately to the grinding operation as aforesaid.

3. The steps in a method of performing a grinding operation upon a workpiece which comprise supplying separately to the place of grinding contact of the grinding wheel with the work-piece and to the workpiece an active grinding-promoting liquid and a coolant liquid respectively

for promoting grinding action by the grinding wheel and for abstracting heat produced by the grinding operation respectively, said two liquids being mutually insoluble, collecting the resultant mixture of commingled liquids, separating out a major portion of one of the liquids from the mixture, completing the separation of the remainder of the mixture by the aid of heat, abstracting heat from at least one of the liquids separated out by the aid of heat, and returning separated active liquid and coolant liquid separately to be supplied separately to the grinding operation as aforesaid.

4. The steps in a method of performing a grinding operation upon a workpiece which comprise supplying separately to the place of grinding contact of the grinding wheel with the work-piece and to the workpiece an active grinding-promoting liquid and a coolant liquid respectively for promoting grinding action by the grinding wheel and for abstracting heat produced by the grinding operation respectively, said two liquids being mutually insoluble, separating the resultant mixture of commingled active liquid and coolant liquid, and returning them separately for resupply separately to the grinding operation as aforesaid.

5. The steps in a method of performing a grinding operation upon a workpiece which comprise supplying separately to the place of grinding contact of the grinding wheel with the work-piece and to the workpiece an active grinding-promoting liquid and a coolant liquid respectively for promoting grinding action by the grinding wheel and for abstracting heat produced by the grinding operation respectively, said two liquids being mutually insoluble, separating the resultant mixture of commingled active liquid and coolant liquid, and returning each at substantially constant temperature for resupply separately to the grinding operation as aforesaid.

6. The steps in a method of performing a grinding operation upon a workpiece which comprise supplying separately to the place of grinding contact of the grinding wheel with the work-piece and to the workpiece an active grinding-promoting liquid and a coolant liquid respectively for promoting grinding action by the grinding wheel and for abstracting heat produced by the grinding operation respectively, said two liquids being mutually insoluble, separating the resultant mixture of active liquid and coolant liquid, and returning them separately, with at least one of them at constant temperature, for resupply separately to the grinding operation as aforesaid.

7. The steps in a method of performing a grinding operation upon a workpiece which comprise supplying separately and respectively at a low rate and high rate a grinding promoting liquid and a coolant liquid to the place of grinding engagement of the grinding wheel with the workpiece and to the workpiece, said coolant liquid and said grinding-promoting liquid having different physical properties adapting them respectively for taking up heat and for promoting grinding action, collecting the resultant mixture of commingled grinding liquid and coolant liquid with the coolant liquid preponderant over the grinding liquid in the mixture, separating out from the mixture the major portion of the coolant liquid contained therein, separating out the grinding liquid from the remaining portion of the mixture, and returning the separated

grinding liquid and coolant liquid separately for resupply to the grinding operation as aforesaid.

8. The steps in a method of performing a grinding operation upon a workpiece which comprise supplying a coolant liquid in relatively large volume and low velocity to the workpiece contiguous to the place of grinding contact between the grinding wheel and the workpiece, and supplying to the place of grinding engagement between the grinding wheel and the workpiece a grinding-promoting liquid free from substantial commingling therewith of said coolant liquid, said coolant liquid and said grinding-promoting liquid having different physical properties adapting them respectively for taking up heat and for promotion of grinding action.

9. The steps in a method of performing a grinding operation upon a workpiece which comprise supplying a coolant liquid in relatively large volume and low velocity to the workpiece contiguous to the place of grinding contact between the grinding wheel and the workpiece, and projecting a grinding-promoting liquid to the region of grinding engagement of the grinding wheel with the workpiece at a velocity effective to prevent material deflection of projected grinding liquid by the coolant liquid, said coolant liquid and said grinding-promoting liquid having different physical properties adapting them respectively for taking up heat and for promotion of grinding action.

10. The steps in a method of performing a grinding operation upon a workpiece which comprise applying a coolant liquid to the workpiece in the region of the engagement of the grinding wheel with the workpiece and substantially preventing material entry of the coolant liquid into the grinding contact of the grinding wheel and the workpiece by supplying to the surface of the grinding wheel a grinding-promoting liquid that is not readily miscible with the coolant liquid to form on the grinding wheel surface substantially a barrier-like liquid film substantially barring direct contact of the liquid coolant with the active grinding wheel surface.

11. The steps in a method of performing a grinding operation comprising applying a coolant liquid to the workpiece adjacent the region of grinding engagement between the grinding wheel and the workpiece and preventing substantial entry of coolant liquid into the grinding contact of the grinding wheel and the workpiece by applying to the moving grinding wheel surface in advance of its engagement with the workpiece a grinding-promoting liquid that is not readily miscible with the coolant liquid and thereby cause the moving grinding wheel surface to carry into the grinding contact a layer-like covering of grinding-promoting liquid and thereby form a barrier to the direct engagement of coolant liquid with the grinding wheel.

12. The steps in a method of performing a grinding operation upon a workpiece which comprise applying a coolant liquid to the workpiece adjacent the region of grinding engagement between the grinding wheel and the workpiece and preventing material entry of coolant liquid into the grinding contact between the grinding wheel and the workpiece by forcing a stream of grinding-promoting liquid that is not readily miscible with the coolant liquid into the grinding contact and from a point that is on the trailing side of the grinding contact to oppose the actions caused by the movement of the grinding wheel surface away from the grinding con-

tact and to form substantially a liquid barrier between the coolant liquid and the grinding wheel surface adjacent the grinding contact.

13. The steps in the method of performing a grinding operation which comprise effecting reversible relative working strokes between the grinding wheel and the workpiece so that on one stroke the relative movement is with the direction of movement of the grinding wheel surface and on reverse stroke is in the opposite direction, applying a liquid coolant to the workpiece and preventing material entry of coolant liquid into the grinding contact between grinding wheel and workpiece by utilizing, on one working stroke, the movement of the surface of the grinding wheel in a direction toward the grinding contact to carry into the latter a continuous layer-like stream of grinding-promoting liquid that is not readily miscible with the coolant liquid and by forcing, on the reverse stroke, a continuous stream of said grinding-promoting liquid into the grinding contact in a direction that is opposed to the direction of movement of the grinding wheel surface, thereby during each stroke, to form substantially a barrier between the coolant liquid and the grinding wheel surface.

14. A method as claimed in claim 13 which comprises also the steps of substantially halting the supply of grinding-promoting liquid substantially at the end of each working stroke.

15. A method as claimed in claim 13 which comprises also the steps of substantially halting the supply of coolant liquid substantially at the end of each working stroke.

16. A method as claimed in claim 13 which comprises also the steps of substantially halting the supply of grinding-promoting liquid and coolant liquid substantially at the end of each working stroke.

17. A grinding apparatus comprising a work holding means and a grinding wheel for grinding the work, means for supplying separately to the place of grinding contact of the grinding wheel with the work and to the workpiece an active grinding-promoting liquid and a cooling liquid respectively for promoting grinding action by the grinding wheel and for abstracting heat produced by the grinding operation, said liquids being mutually insoluble and being of different specific gravities, means for treating the resultant swarf-containing mixture of active liquid and coolant liquid and emulsions thereof to separate them and comprising means for separating out at least some of the swarf, means utilizing the difference in specific gravities of the two liquids for separating a major portion of the liquid coolant for re-supply thereof to the work, means utilizing heat to break down emulsified portions of the remainder of the mixture and to increase the fluidity thereof to facilitate separation therefrom of swarf and to separate out the active liquid for re-supply thereof to the grinding contact, means for abstracting heat from the separated active liquid to lower its temperature, and means for supplying the separated coolant liquid and lower-temperature active liquid respectively to the work and the grinding contact.

18. A grinding apparatus comprising a work holding means and a grinding wheel for grinding the work, means for supplying separately to the place of grinding contact of the grinding wheel with the work and to the workpiece an active grinding-promoting liquid and a cooling liquid respectively for promoting grinding action by the

grinding wheel and for abstracting heat produced by the grinding operation, said two liquids being mutually insoluble, means for collecting the mixture of commingled active liquid and coolant liquid and emulsions thereof produced at the place of grinding, means including heating means to separate out the active liquid from the coolant liquid in said mixture, means for withdrawing heat from the separated liquids, and means for re-supplying the lower-temperature separated coolant liquid and active liquid to said first mentioned supplying means.

19. A grinding apparatus comprising a work holding means and a grinding wheel for grinding the work, means for supplying separately to the place of grinding contact of the grinding wheel with the work and to the work-piece a grinding liquid and a cooling liquid respectively for promoting grinding action by the grinding wheel and for abstracting heat produced by the grinding operation, means for collecting commingled grinding liquid and coolant liquid and swarf resulting from the grinding operation, means for separating said mixture of commingled liquids and swarf into its three constituents and for withdrawing heat from at least the coolant liquid constituent thereof, and means for resupplying the separated grinding liquid and the separated lower-temperature coolant liquid to said first-mentioned supply means.

20. The steps in a method of performing a grinding operation upon a work piece which comprise directing a multi-mouthed discharge device that has a large mouth and several small mouths toward the region of grinding engagement between a grinding wheel and the work piece, discharging from the large mouth of the device a coolant liquid toward the work piece in relatively large volume and rate to withdraw heat from the work piece produced by the grinding operation on the latter, and discharging from the small mouths of said device a plurality of streams of a grinding-promoting liquid that is not readily miscible with and is of different specific gravity from that of said coolant liquid, said small mouths directing the streams in substantially side-by-side relation to move in substantially a broad front to the grinding contact between the grinding wheel and the work piece and along that side of the coolant liquid emerging from the first mentioned mouth that is toward the grinding wheel surface and thereby, aided by its substantial non-miscibility with said coolant liquid, form substantially a barrier of grinding-promoting liquid against material entry of coolant liquid into the grinding contact, collecting the two liquids and separating them and returning them separately for resupply to their respective discharge mouths.

21. The steps in a method of performing a grinding operation upon a work piece which comprise directing a large-mouthed discharge device to discharge a large-volume low-velocity column of coolant liquid onto the work piece at points in the latter closely adjacent to the region of grinding contact between the grinding wheel and the work piece to abstract heat resulting from the grinding operation and directing a small-mouthed discharge device to discharge a stream of grinding-promoting liquid that has different physical characteristics from those of said coolant liquid adapting it for promotion of grinding action and that is not readily miscible with said coolant liquid, to the grinding contact between the grinding wheel and the work piece and at a

velocity to form, aided by its substantial non-miscibility with said coolant liquid, substantially a barrier of grinding-promoting liquid between the column of liquid coolant and the grinding wheel surface and by said liquid barrier substantially oppose material entry of coolant liquid to the grinding contact.

22. A grinding apparatus comprising a work holding means and a grinding wheel for grinding the work, a plurality of liquid discharge means comprising a relatively large-flow discharge device and a multi-nozzled discharge device directed generally toward the region of grinding contact of the grinding wheel with the work, said first device being directed to discharge a relatively copious column of liquid onto the work closely adjacent to the grinding contact and said other device having its nozzles arranged in spaced relation to project a plurality of substantially side-by-side streams of liquid and having means dirigibly mounting at least certain of said nozzles for thereby setting the relative directions of the discharge trajectories to provide a spread of flow substantially commensurate with the width of the face of the grinding wheel at the grinding contact, said multi-nozzled device being directed to discharge said side-by-side streams toward the grinding contact along a path intermediate of the grinding wheel surface and the path of liquid discharged by the first mentioned mouth, means for supplying a coolant liquid to said large-flow device for discharge onto the work as aforesaid, and means for supplying a grinding-promoting liquid, that has different physical characteristics from those of said coolant liquid adapting it for promotion of grinding action, to said multi-nozzled device for discharge from said nozzles and in a spread of flow substantially commensurate with the width of the grinding wheel face at the grinding contact and along said intermediate path to thereby form substantially a liquid barrier against material access of coolant liquid to the grinding contact, said two liquids being mutually substantially insoluble.
23. A grinding apparatus comprising a work holding means and a grinding wheel for grinding the work, discharge means for directing in relatively large volume a flow of coolant liquid onto the work adjacent the grinding contact for abstracting heat produced in the work by the grinding operation, means for supplying a grinding-promoting liquid to the grinding contact, said supplying means comprising a liquid discharge device discharging grinding-promoting liquid substantially onto the grinding face of the grinding wheel at points closely adjacent the grinding contact and spaced from said flow of coolant liquid to thereby oppose material entry of the latter into the grinding contact, said coolant liquid and said grinding-promoting liquid being mutually insoluble and not readily miscible and having different physical properties adapting them respectively for taking up heat and for promotion of grinding action, means comprising a receiver for collecting the commingled coolant liquid and grinding-promoting liquid and operating, in response to certain of their different physical characteristics, to separate them, and two conduit means for returning the separated liquids respectively to said two discharge means.
24. An apparatus as claimed in claim 23 in which said second-mentioned discharge means comprises means for supplying the grinding promoting liquid directly to the grinding wheel surface to substantially cover the latter therewith

and thereby, aided by the aforesaid characteristics of substantial mutual insolubility and non-miscibility of said liquids, substantially bar the liquid coolant from material engagement with the grinding wheel surface.

25. An apparatus as claimed in claim 23 in which said second-mentioned discharge means comprises nozzle means for projecting the grinding-promoting liquid along said path at substantial velocity and by its velocity effect, aided by the aforesaid characteristics of substantial mutual insolubility and non-miscibility of said liquids, substantially bar material access of the coolant liquid to the grinding contact.

26. A grinding apparatus comprising work holding means and a grinding wheel and means for effecting relative movement in reversible working strokes between the grinding wheel and the work, means forming respective sources of supply for a coolant liquid and a grinding-promoting liquid that have different physical properties adapting them respectively for taking up heat and for promotion of grinding action, means for applying coolant liquid from its aforesaid source to the work to abstract heat produced during grinding action on the latter, and means for supplying grinding-promoting liquid to the grinding contact and for preventing material entry of coolant liquid into the grinding contact between the grinding wheel and work, said last mentioned means comprising two means respectively at the leading and trailing sides of the

grinding wheel and each comprising a discharge device for supplying grinding-promoting liquid from its aforesaid source to the grinding contact along a path to form substantially a liquid barrier against material entry of coolant liquid into the grinding contact and to oppose tendency of coolant liquid to be entered into grinding contact under the effects of said reversible working strokes, said coolant liquid and said grinding-promoting liquid being mutually substantially insoluble and not readily miscible, and means utilizing said last mentioned characteristics of the two liquids for separating them, for resupply thereof to their aforesaid respective sources.

27. An apparatus as claimed in claim 26 in which each of said last-mentioned two means is provided with valve means, and means operating synchronously with said reversible working strokes between the grinding wheel and the work for controlling said valve means.
